Primary Examiner—Stella Reid

Attorney, Agent, or Firm—Synnestvedt & Lechner

[57] CLAIM

The ornamental design for a female sanitary protection pad, as shown and described.

DESCRIPTION

FIG. 1 is a perspective view of a female sanitary protection pad showing my new design.

FIG. 2 is a top plan view thereof.

FIG. 3 is a bottom plan view thereof.

FIG. 4 is a side elevational view thereof.

FIG. 5 is an end elevational view thereof.

FIG. 6 is a perspective view thereof with the paper backing removed.

The cross-line pattern, which is partially shown for ease of illustration, is intended to represent a conventional fabric.
